UNITED STATES PATENT OFFICE.

HARALD NIELSEN, OF LONDON, ENGLAND, ASSIGNOR OF ONE-HALF TO BRYAN LAING,
OF HATFIELD, HERTS, ENGLAND.

ROTARY RETORT.

Application filed February 4, 1924. Serial No. 690,678.

To all whom it may concern:

Be it known that I, HARALD NIELSEN, a subject of the King of Denmark, residing at 13 Firs Avenue, Muswell Hill, London, 5 N. 10, England, have invented certain new and useful Improvements in or Relating to Rotary Retorts, of which the following is a specification.

This invention relates to retorts, kilns, 10 dryers or the like (hereinafter termed retorts) of the kind that are divided longitudinally into a suitable number of zones or compartments by means of plates or baffles disposed transversely across the retort from side to side thereof, the plates or baffles being usually constituted by mutilated discs so as to leave a space between the projecting or free end of each plate or baffle and the wall of the retort through 15 which the material undergoing treatment 20 may pass.

According to the present invention certain or each of the baffles are provided at their free ends with a shelf or shelves constituted by an extension or by a plate or plates disposed transversely, or extending laterally, of the baffles and preferably reaching at its ends to the interior wall of the retort.

30 The baffles which are preferably upright or vertically disposed may be curved at the points where they are connected to the retort as also at the junctions between the laterally projecting shelves and the uprights 35 so as to avoid the formation of right angled pockets.

The laterally disposed shelves, in combination with the baffles serve to divide up to as large an extent as desired the sectional area of the retort, the only space left 40 for the passage of the gaseous heating medium being restricted to the opening left between the top or free end of each baffle, and the interior wall of the retort.

45 Baffles of this character are very effective in bringing the heating medium into more intimate contact with the material undergoing treatment on account of the natural tendency of the gaseous heating medium to travel along the top of the retort. Furthermore, and by employing suitable laterally projecting shelves attached to the aforesaid baffles the gas is forced to pursue a sinuous path, so that the baffles and shelves situated 50 in the lower part of the retort, and arranged

alternately to those attached to the upper part of the retort, can also be made equally effective.

I have found that it is preferable, particularly when carbonaceous material is being distilled or heated, to discharge the same into an annular container attached to and revolving with the retort, so as to allow it to cool down in a non-oxidizing atmosphere before being discharged to the outside atmosphere, and according to a further feature of the said invention the treated material may be discharged from the retort into the aforesaid annular container through an opening which is controlled by 60 means of a valve, slide or the like operated by hand or preferably by steam or compressed air.

In order that the said invention may be clearly understood and readily carried into effect the same will now be described more fully with reference to the accompanying drawing, in which:

Figure 1 is a longitudinal section of a 65 rotary and inclined retort constructed according to one embodiment of the present invention.

Figure 2 is a section on the line 2—2 of Figure 1.

Figure 3 is a section of a modified form 85 of retort in which the projecting baffles are displaced or staggered relatively to one another along the length of the retort so as to impart a whirling movement to the gases and thus bring the same into more intimate 90 contact with the material undergoing treatment.

Figure 4 is a longitudinal section of a 95 retort showing more or less diagrammatically a number of modified forms of the projecting baffles and shelves, any of these forms being capable of being employed either individually or collectively in lieu of the shelves shown at Figures 1, 2 and 3.

A is the body of the retort and B, B are 100 the baffles attached to the inner wall of the retort and projecting outwards to beyond the axis thereof, the baffles in the various embodiments shown being also provided at their projecting outer ends with further 105 plates or shelves C, C disposed transversely or extending laterally of the baffles B, B. D is a hopper through which the material which is to undergo treatment enters the 110 retort. E is a screw conveyor by which the

material is fed from the hopper to the interior of the retort. F is a so-called sealing chamber disposed at the exit end of the retort through which the material may be discharged in the manner hereinafter described. In the example shown the rotary retort is arranged to be heated internally, for example, by combustion gases or by the so-called sensible heat of water or producer gas which is admitted to the retort through the inlet G, the combined retort and heating gases being drawn off through the exit opening H.

During rotation of the retort, the relative positions of the alternately disposed shelves C, C and baffle plates B, B will be continuously reversed or altered with reference to the horizontal, and, as the material undergoing treatment travels along the retort, portions of the same will continually be picked up or showered upon the laterally projecting portions of the shelves. At the same time the heating medium will be compelled, as shown by the arrows at Figure 1, to pursue a sinuous, tortuous or zig-zag path and, as the passages S, S between the shelves C, C and the retort walls through which the medium travels will be partly obstructed by the material undergoing treatment, the latter will be brought into most intimate contact with the heating medium. Furthermore, owing to the continuous alteration in the position of the baffles and shelves the material will be continuously stirred and displaced, thus presenting new surfaces to the action of the heating medium. As the gaseous heating medium is forced to pursue a sinuous path in passing along the retort, the gas passage will be practically twice the length of the retort; consequently the heat of the gaseous medium will be utilized to a far greater extent than heretofore and a considerable saving thereby effected. The greater part of the dust carried along by the heating medium will also be effectually trapped by the baffle plates and shelves.

Neither the vertical baffles B, B or the horizontal shelves C, C need necessarily be plain, but can be bent, corrugated or of any other desired shape. Furthermore, and as shown at Figure 3, the shelves C, C and baffles B, B may be disposed in such a manner that, when looking through the retort from end to end thereof, they present a twisted or helical passage for the gaseous heating medium.

It will be understood that in cases where carbonaceous materials are being treated for the distillation of the same with the removal and recovery of the desired volatile constituents, the gaseous heating medium should preferably not contain any free oxygen in quantities which would cause combustion of the evolved volatile matters, while in cases where noncarbonaceous materials are being

treated it will be possible to employ as desired either a reducing or oxidizing gaseous heating medium.

The baffles may be curved at the points B' and B² (Figure 1) where they join the retort, as also at the junction C' and C² between the projecting shelves C and the baffles B so as to avoid the formation of right angled pockets.

The baffles or the shelves, plates, or both may, if desired, be inclined at any suitable angle to one another or to the vertical or both, or they may be curved so that they form segments or sections of a helix. The lateral shelves at the outer ends of the baffles may also be inclined (either inwardly or outwardly) or curved, corrugated or of other suitable formation and in cases where only a single laterally projecting shelf is employed on each baffle (as shown for example at B', B' (Figure 4)) it may if desired, be formed integral therewith. A combination of any of these arrangements, including plain upright shelves, can also be employed.

A suitable combination of a number of the aforesaid arrangements referred to in the preceding paragraph is shown at Figure 4, where single and combined laterally projecting baffles are shown attached to the outer projecting ends of the depending baffles.

When the material reaches the exit end of the retort, in the particular construction of retort shown at Figure 1, it may be intermittently discharged through an opening I in the wall of the retort into the sealing chamber F by means of a slide valve J, which is operated by the steam cylinder X that is connected to the outer wall of the body A by any suitable means, such as the bolts K. After the material has been sufficiently cooled down within the chamber F, it is discharged to the outside atmosphere through an opening I' controlled by means of a second slide valve J' that is also operated by a steam cylinder Y, which is secured to a bracket Z on the chamber F by the bolts L. Instead, however, of operating the slide valves by steam or compressed air they may be operated by some mechanical arrangement or by hand.

If steam is to be used in the cylinders which operate the slide valves J, J', the exhaust steam from the cylinders may be conducted through the pipes J³—J³ into the sealing chamber F so as to assist in cooling down the material undergoing treatment before it is discharged to the atmosphere.

What I claim and desire to secure by Letters Patent of the United States is:—

1. A rotary retort of the class described, comprising an elongated inclined tubular body, a series of baffle plates distributed along the interior of said body, each of said baffle plates being connected at one edge to said body, the plane of said plates extending

transversely to said body, and a shelf secured to the opposite edge of each of said plates and extending in opposite directions therefrom substantially at right angles to 5 said plate.

2. An inclined elongated rotary retort for the heat treatment of solid material comprising baffle plates projecting inwardly therefrom and dividing the interior of the retort 10 into a series of compartments, an annular member disposed around and attached to the lower end of the retort defining with the wall of said retort a closed annular chamber therearound, said retort having an opening 15 therein connecting the retort with said annular chamber, said annular chamber having an opening leading from the same to the atmosphere, valves for controlling said openings, steam cylinders for intermittently 20 operating said valves, and means for conducting the exhaust steam from said cylinders into the annular chamber so as to as-

sist in cooling down the material before it is discharged to the atmosphere.

3. A retort comprising an inclined elongated rotary hollow body and an annular member around, and attached to, the lower end of said body defining with the wall of said body a closed annular chamber therearound, said body having an opening communicating the body with said annular chamber, said annular chamber having an opening leading from the same to the atmosphere, discharge valves for controlling said openings, steam cylinders for operating said valves, means for conducting the exhaust steam from said cylinders into the annular chamber so as to assist in cooling down the material before it is discharged to the atmosphere, and means for conducting the 40 highly superheated steam from the annular chamber to said body for the purpose specified.

HARALD NIELSEN.
